UNITED STATES PATENT OFFICE.

RALPH BAGGALY, OF PITTSBURG, PENNSYLVANIA.

CONVERTER.

SPECIFICATION forming part of Letters Patent No. 746,238, dated December 8, 1903.

Application filed February 12, 1903. Serial No. 143,010. (No model.)

To all whom it may concern:

Be it known that I, RALPH BAGGALY, of Pittsburgh, Allegheny county, Pennsylvania, have invented a new and useful Converter, 5 of which the following is a full, clear, and exact description, reference being had to the accompanying drawings, forming part of this specification, in which—

Figure 1 is a side elevation of the converter, 10 partly in longitudinal section. Figs. 2 and 3 are elevations of the opposite ends respectively. Fig. 4 is a vertical cross-section on the line IV IV of Fig. 1.

My invention relates to an apparatus for 15 refining metal mattes or compounds by the bessemerizing or converting process in a quicker, cheaper, and more efficient manner than at present prevails.

It is well known that the heat in the early 20 stages of converting is increased and decreased and can be thus readily controlled by the volume of blast alone. In the present practice, however, the heat of converting must be kept comparatively low, because the 25 converter as at present used will be quickly destroyed by higher heats. For this reason the blast is delivered to the converter in moderate volume, and the converting process is therefore continued sometimes for more than 30 three hours simply because the converter-walls will not admit of higher temperatures being used. In addition to this in the present converters it is impossible to use brick linings notwithstanding the fact that such 35 linings would be much cheaper than others, because of the fact that it has been found that the heat of the interior walls will rapidly penetrate any kind of brick and will weaken and destroy the metal shell of the 40 converter itself.

The refining of copper by my process consists simply in the elimination of various elements successively in the order in which each can be oxidized.

45 The atmosphere furnishes the cheapest source of supply of oxygen, and the reason that copper, gold, silver, nickel, and cobalt are freed from their impurities through the action of the converting-blast is because iron, 50 arsenic, selenium, tellurium, bismuth, antimony, lead, and other elements are oxidized, and thus eliminated before oxidizing com-

mences in the case of the above-mentioned metals, which it is desired to recover. Hence the larger the volume of air that is delivered 55 into the molten mass the greater the resulting heat and the quicker the desired result is accomplished.

In my improved converter I use two, three, or even five times the volume of blast in a 60 given time that is used in present practice, and I accomplish a given amount of work for this reason in a fraction of the time at present required. The reason that has prevented manufacturers heretofore from increasing the 65 volume of the blast is because their converters will not stand the greater heat.

Should converters as at present used be provided with water-jackets or even with coils for the circulation of water or air through 70 the lining at the latter portion of the converting process, when the heat begins to fail through the reduced percentages of oxidizable impurities or when the matte has reached approximately seventy per cent. or eighty per 75 cent of copper the contents of the converter will solidify and the process will be brought to a standstill and the desired refining rendered abortive. In the ordinary converter not provided with water-jackets, even with 80 the addition of blocks of cord-wood from time to time in a feeble effort to maintain the temperature until the process can be rushed through to completion, great difficulty is experienced and great expense is incurred. 85 Sometimes the refining process is brought to a standstill through the obstruction of the blast by the formation of "copper" noses on the ends of the twyers in the converter. The final operation is thus rendered erratic 90 and uncertain and is at times unduly hastened in order to complete the work before the mass solidifies. The net result of these conditions is necessarily poor work or at all events not such good and perfect work as 95 would be possible where the temperature of the molten mass can be regulated at will and held just high enough so that it would be impossible for copper noses to form.

I provide for and counteract the injurious 100 effects that would otherwise result from the greatly increased volume of blast, with its consequent increased heats in the early stages of the converting process, by means of abun-

dant streams of cooling-water flowing through a number of narrow metal jackets, which cooling streams are capable of regulation at will in each separate jacket, while during the 5 later stages of the converting process I supply to the converter the auxiliary heat of a flame that is also capable of regulation at will and by means of which I am enabled to produce the best work and with the greatest 10 economy, dispensing entirely with the present tedious, expensive, and unworkman-like practice of removing copper noses by steel bars, sledge-hammers, and manual labor.

Fluxes of any kind, whether they be silica, 15 iron, lime, dolomite, or other flux, will be quickly melted through the intense heat and violent agitation of the molten mass produced by the great volume of air and will be quickly mixed and readily taken up by the mass as a 20 means of forming the desired slag.

The converter shown in the drawings is of barrel shape formed with an interior refractory lining, exterior water-jackets, and a metal cradle or frame by which the structure 25 is held together.

22 are metal end plates of the converter, which are preferably dished and are connected by longitudinal bars or channels 3, which constitute therewith a supporting-cradle for 30 the water-jackets and the contained refractory lining. These water-jackets are made of parallel sections 4 4, which are shaped to suit the contour of the converter and are preferably long and narrow. They are set 35 edge to edge, being connected by bolts passing through marginal flanges 5, and they are provided with transverse flanges 6, which fit against the sides of one of the channel-bars, as shown in Fig. 4, and are secured thereto 40 and to each other by bolts 7. The water-jackets at the ends of the converter are constituted by hollow plates 8 8', set on the inner side of the end plates 2 2.

Each of the jacket-sections 4 4 and each 45 of the sections 8 8' has a water-inlet 9, communicating with a water-supply pipe 10, which derives its water from a swiveled water connection 11 at the axis of rotation at one end of the converter, and at the upper 50 end each of the sections has an outlet-passage 12, connecting with a pipe 13, leading to a vertical flexible stand-pipe 14, which being elevated insures that the water-jackets are always kept full of water and that escape 55 of bubbles of steam and air can freely occur. Being flexible the stand-pipe does not interfere with the rotation of the converter.

Inside the water-jackets is a refractory lining 15, made of bricks composed of chrome 60 ore, magnesite, silica, or dolomite, or the lining may be made of plastic refractory material rammed in place. I prefer, however, to make the lining of bricks. This has not hitherto been done in copper-converters, and 65 I am enabled to do it by the use of the water-jackets, which keep the outer surface of the converter from becoming overheated.

The upper part of the converter is constituted by a removable section 16, composed of a metal shell 17 with an interior refractory 70 lining, and it is provided with suitable lifting rings or lugs 18, by which when desired it can be removed to afford access to the interior for purposes of repair.

The converter has twyers 19 extending 75 through the refractory lining and through the water-jackets to a wind-box 20, which derives its supply of air from a pipe 21, swiveled at the end of the converter in the axis of rotation.

The converter is preferably mounted on 80 wheels 22, which are journaled in a foundation 23, the end plates 2 2 being formed with a peripheral rim 24, which bears on the wheels. The wheels 22 at one end of the converter are provided with flanges, which engage and hold the rim 24; but the wheels 22 at the other end are unflanged, so as to permit free longitudinal expansion of the converter.

In order to rotate the converter, I provide 85 it at one end with a segmental pinion 25, engaging a rack 26, which may be reciprocated by a power-cylinder 27 or other suitable means. This rack may be held in engagement with the pinion by a cam 28, which bears against the back of the rack and constitutes a guide. By rotating the cam the 90 rack is freed and can be disengaged from the pinion.

S is a spout by which fluxes can be delivered to the converter, Fig. 4.

The converter is provided with means for supplying the heat of a flame to the surface of the charge at the end of the blow when 105 nearly all the bases of the matte have been oxidized and the heat of oxidation has thus failed. For this purpose I introduce at the end of the converter one or more burners 29, adapted to supply a jet of gas or of oil sprayed 110 with air or steam, and I am enabled thereby to generate in the converter an intense degree of heat as may be required. The pipes 30 and 31, which supply the burner, are provided with swinging joints, so that they will 115 not interfere with the rotation of the converter.

In using the converter it is charged with molten matte, and jets of air are blown into it from the twyers, the air being supplied in 120 large volume, as above stated. This effects the conversion with greater rapidity and with the generation of more intense heat than is at present required, and I am enabled to do this by the use of the water-jackets back of 125 the refractory lining, which prevent the destruction of the converter-shell at the beginning of the blow when the oxidation and generation of heat are rapid, and by the use of the burner 29, from which I supply heat to 130 the surface of the charge toward the end of the blow when the oxidation and heat of chemical combination fail. By the auxiliary heat of the burner I can retain the matte

during the final stage of the blow in the necessary hot and liquid condition without danger of chilling it by the water in the jackets or by the cooling effect of the large blast of air. The heat from the burner also prevents the formation of copper noses at the twyers, which heretofore have constituted a source of annoyance and expense.

It will thus be seen that by the employment of a water-jacket I can increase the air-blast and generate in my converter at the early stages of the blow greater heat than heretofore without destroying the converter and can convert the copper in a shorter time, and by using means for introducing the heat of a flame above the charge I am enabled to prevent the freezing of the charge which by reason of the cooling influence of the water-jacket and the air-blast would be more apt to occur in my converter at the later stages of the blow when the heat of oxidation fails than in converters now in use. By the term "copper-converter" employed in the claims I mean a converter for refining copper which by reason of the water-jacket and the means for producing the heat of a flame above the charge can be employed with a larger volume of air than is now ordinarily employed and can convert the charge more quickly with a higher temperature at the earlier stages of the blow and without danger of freezing at the end of the blow.

The advantages of my converter will be appreciated by those skilled in the art. It produces converted copper quickly and with a minimum of labor and yields it at a temperature suitable for casting or for transfer in molten condition to a refining-furnace. It

also enables me to use silica and other fluxes in the charge instead of depending upon the lining for fluxing the impurities of the charge.

I claim—

1. A copper-converter having twyers, a refractory lining, a water-jacket back of the lining, and means for supplying the heat of a flame to the converter above the copper-level; substantially as described.

2. A copper-converter having twyers, a refractory lining, a water-jacket back of the lining, means for supplying the heat of a flame to the converter above the copper-level, and means for tipping the converter; substantially as described.

3. A copper-converter having a water-jacket and a burner for supplying heat to the surface of the charge; substantially as described.

4. A copper-converter having end plates, a metal framework connecting them and constituting a cradle, twyers, means for supplying heat above the copper-level, and water-jackets and a refractory lining contained within the jacket; substantially as described.

5. A copper-converter having water-cooling devices adapted to prevent overheating of the converter at the early stages of the blow, and having a burner adapted to supply heat to the surface of the charge at the end of the blow when the heat of oxidation fails; substantially as described.

In testimony whereof I have hereunto set my hand.
